UNITED STATES PATENT OFFICE.

WILLIAM O. CONWAY, OF MOUNT GILEAD, OHIO, ASSIGNOR OF ONE-HALF
TO LOUIS K. POWELL, OF SAME PLACE.

HOISTING APPARATUS.

SPECIFICATION forming part of Letters Patent No. 434,701, dated August 19, 1890.

Application filed January 10, 1890. Serial No. 336,501. (No model.)

To all whom it may concern:

Be it known that I, WILLIAM O. CONWAY, of Mount Gilead, in the county of Morrow and State of Ohio, have invented a new and Improved Hoisting Apparatus, of which the following is a specification.

The object of this invention is to provide a portable hoisting apparatus of simple construction which can be used for hoisting purposes in general, but which is particularly designed for the use of butchers in slaughtering animals.

This improved hoisting apparatus is illustrated in the following drawings, in which Figure 1 is a perspective view of the apparatus, showing it in its elevated position and indicating its lowered position by dotted lines. Fig. 2 is a side view, partly in vertical section, of the main hoisting-beam and its accessories; and Fig. 3 is a face view of the upper portion of the hoisting apparatus.

This hoisting apparatus comprises as its main structural features a main hoisting-beam A and two weight-supporting beams B. The main hoisting-beam A has journaled in it, near its top and bottom, respectively, two pulleys C C, and over these pulleys passes an endless hoisting sprocket-chain D. Secured to this endless sprocket-chain is a sliding carrier E. This sliding carrier comprises a sliding plate F, which slides against the inner face of the main hoisting-beam A, between said beam and the sprocket-chain. This plate is secured to the sprocket-chain by means of tongues G, which are passed through certain of the chain-links and securely fastened therein, so that as the chain is moved the sliding carrier will travel therewith.

To the sliding carrier E are pivotally connected the upper ends of the two weight-supporting beams B B. This pivotal connection with the sliding carrier is preferably secured by means of a cross-shaft H, journaled in ears I I, formed on the carrier-plate F, upon the projecting ends of which shaft the weight-supporting beams turn, being retained in position thereon by flanges J J on the ends of the shaft. The upper end of each weight-supporting beam B is formed with an open slot K, which passes over one end of the shaft H, so that the weight-supporting beams can

be readily attached to and detached from the shaft. The lower ends of the three beams A B B are provided with steel points L L, 55 these points being adapted to be thrust into the ground so as to maintain the feet of the several beams in fixed relative positions while the apparatus is being used. It will be evident that as the sprocket-chain is 60 moved in either direction the sliding carrier will be moved therewith.

For the purpose of moving the chain a hand-lever M is pivotally connected by a hinge or otherwise to the main hoisting-beam A. This lever M has a slot N near its pivotal connection, and through this slot the sprocket-chain passes. On the under side of the lever is carried a longitudinally-sliding spring-actuated latch O, which engages the 70 links of the sprocket-chain one by one. Whenever the lever M is depressed, the latch O engages with one of the links of the sprocket-chain, thus causing the chain to rotate and raising that portion of the chain to which the 75 sliding carrier is attached. Movement of the chain in the opposite direction (which would be the direction to lower the sliding carrier) is prevented by means of a spring-catch P, located on the under side of the main supporting-beam. This catch automatically engages the successive links of the sprocket-chain and so prevents the backward movement thereof. Consequently when the hand-lever is elevated it has no effect upon the 80 movement of the chain, the sliding spring-latch O riding over the links of the chain, its lower end being beveled for this purpose. Consequently by alternately lowering and raising the lever the sliding carrier attached 85 to the chain can be elevated until it reaches the upper pulley on the main hoisting-beam.

In using the apparatus the steel points of the several beams are fixed in the ground at the proper points, and the main hoisting-beam 95 is placed in an almost vertical position, as is indicated by the dotted lines in Fig. 1. The sliding carrier thus occupies its lowermost position, and the two weight-supporting beams B B occupy an approximately horizontal position. The weight to be lifted is then attached 100 to the weight-supporting beams.

The means for attachment will be determined by the purpose to which the apparatus

is to be put. The means shown are those preferably employed for hoisting animals during the process of slaughtering. Each of the weight-supporting beams is provided with a bracket or eye Q, and upon these brackets or eyes is supported a cross-bar or "gambol," over the projecting ends of which are placed the legs of the animal to be hoisted. The operating-lever is then manipulated and the sliding carrier is moved gradually upward. During this upward movement of the carrier the angles of the several beams A B B constantly change, so that when the sliding carrier reaches its most elevated position the three beams constitute a tripod and are all inclined at approximately the same angle. The tripod thus constituted furnishes a firm support for the animal or other weight which is to be hoisted.

In order to lower the apparatus, it is necessary that the spring-catch should be removed from engagement with the sprocket-chain. To this end a spring-stop R is provided near the bottom of the main beam A, which when pressed upon by the foot encounters the catch P and moves it out of engagement with the hoisting-chain. The sliding latch O on the lever is then moved by hand away from the chain, which is then free to be moved backward by means of the weight of the parts which are supported by the sliding carrier.

It will be seen from this description that I

have provided a simple, strong, and efficient hoisting apparatus, and one which is very 35 easily operated. It can be readily taken to pieces and boxed for transportation in a small space.

I claim as my invention—

1. In a hoisting apparatus, a main hoist- 40 ing-beam, an endless chain carried thereby, and means for moving said chain, in combination with a sliding carrier carried by said chain and two weight-supporting beams connected with said sliding carrier, substantially 45 as set forth.

2. In a hoisting apparatus, a main hoist- 40 ing-beam, pulleys journaled in said beam near to the ends thereof, an endless chain passing around said pulleys, an operating le- 50 ver hinged to said beam and having a spring-latch engaging said chain, a spring-catch for retaining said chain in position, and a movable stop for rendering said catch inoperative, in combination with a sliding carrier 55 connected to said chain, and two weight-supporting beams, the upper ends of which are pivotally connected to said sliding carrier, substantially as set forth.

In witness whereof I have hereunto signed 60 my name in the presence of two subscribing witnesses.

WILLIAM O. CONWAY.
